(57) **CLAIM**

The ornamental design for a bottle handle, as shown and described.

DESCRIPTION

FIG. 1 is a front perspective view of the bottle handle showing my new design.

FIG. 2 is a rear perspective view thereof.

FIG. 3 is a top plan view thereof.

FIG. 4 is a bottom plan view thereof.

FIG. 5 is a left side view thereof.

FIG. 6 is a right side view thereof.

FIG. 7 is a front view thereof.

FIG. 8 is a rear view thereof; and,

FIG. 9 is a perspective view thereof with a bottle shown in broken lines for illustrative purposes only and forming no part of the claimed design.

The portions of the bottle shown in broken lines form no part of the claimed design.
